UNITED STATES PATENT OFFICE.

PETER A. SCHWAB, OF NEW YORK, N. Y.

DOOR LATCH.

Application filed July 3, 1919. Serial No. 308,553.

To all whom it may concern:

Be it known that I, PETER A. SCHWAB, a citizen of the United States, and a resident of New York city, in the county of New 5 York and State of New York, have invented certain new and useful Improvements in Door Latches, of which the following is a specification.

This invention involves certain improvements over the construction shown and broadly claimed in my prior United States Patent 1,250,522 issued December 18, 1917, and includes certain features disclosed and claimed in my Canadian Patent 187,505 10 filed July 8, 1918 and issued November 19, 1918.

In said prior United States patent I have disclosed a new form of latch in which the latch member is mounted to swing and at 20 its free end presents a cam surface which may ride over a roller retainer in closing the door, and an undercut face engaging with the roller, when the door is in closed position at a point beyond the axis of the latter, 25 and in such a way that it effectively resists any attempt to open the door without first manually operating the latch. The strain tending to force the door open, only causes the undercut face of the latch to more firmly 30 grip the roller and prevent the opening of the door.

Among the objects of my present invention are to permit the more easy closing of the door without manual operation of the 35 latch, to render the parts more rigid, strong, and positive in their operation, to permit of the operation of the latch by either a rotatable or swinging handle, to simplify and improve the construction of the latch member, 40 and the attachment of the operating member thereto, to simplify and improve the roller retaining, supporting, and adjusting means, and to provide an improved 45 means for automatically moving the latch into operative position when the door is closed. My improved construction, which may assume various different forms, also embodies all of the various advantages set forth in my prior patents above referred to.

50 In the accompanying drawings:

Figure 1 is a face view of the latch removed from the door and certain parts being broken away.

55 Figure 2 is a top plan or edge view of the construction shown in Figure 1, and in op-

erative relationship to the retainer, and partially showing the door and door casing in outline.

Figure 3 is a view similar to Figure 2 but showing certain of the parts in section. 60

Figures 4, 5, and 6, are perspective views of the latch retainer and its supporting and adjusting means.

Figure 7 is a transverse section through a portion of a door and door casing, showing 65 a modified form of construction, said section being taken substantially on the line 7—7 of Figure 8.

Figure 8 is a section on the line 8—8 of Figure 7. 70

Figure 9 is a section on the line 9—9 of Figure 8.

Figure 10 is a face view of the retainer shown in Figures 7 and 8.

Figure 11 is a view similar to Figure 7, 75 but showing a further modified form.

Figure 12 is an inside face view of the door part of the retainer, detached from the door.

Figure 13 is an edge view of the parts 80 shown in Figure 12, and

Figure 14 is a perspective view of the retainer shown in Figure 11.

In the specific form illustrated in Figures 1 to 6 inclusive, a portion of a door 10 and 85 a door casing or automobile body are illustrated somewhat diagrammatically. The materials and details of construction of such door and casing are unimportant so far as the present invention is concerned. 90 The door casing is provided with a transverse grooved channel or recess within which is set a latch retainer shown particularly in Figures 4, 5, and 6. This includes a metal plate 12 preferably countersunk into 95 the wood or body of the casing 11 and secured in any suitable manner, as for instance, by a pair of screws 13. Secured to this base plate 12 is a second plate 14 having its edges turned up to form lugs 15 and 100 constituting a roller carrier. The lugs constitute journals or supports for a pin upon which is mounted a hollow roller 16 of such length that it is held against longitudinal movement by the flanges 15, 15. 105 The roller retainer is so connected to the base plate that the roller extends in a vertical position and may be adjusted horizontally toward and from the surface of the door or casing wall. As shown, the plate 14 110

has a slot through which extends a retaining screw 17 threaded into an opening in the base plate. By loosening the screw, the roller may be adjusted to bring it to the proper position in respect to the latch to effect the proper retention of the latter as hereinafter described. It may also be adjusted from time to time to take up for wear although by reason of the comparatively frictionless operation of the parts, this is seldom, if ever, necessary. To facilitate the more gradual inward movement of the latch and the easier closing of the door without manual operation of the latch handle, I employ a latch strike plate 18 set at such an angle that the door latch engages with the outer surface thereof and rides along it approximately to the upper or outer surface of the roller. This plate is shown as having side flanges resting upon the plate 14 and positioned between the two roller supporting lugs 15 and held in place by a suitable screw. This strike plate not only guides the latch over the roller in closing the door but also serves to conceal the adjusting screw 17.

Rigidly secured to the door is a plate 20 formed integral with a flange or second plate 21, lying parallel with the plane of the door. This last mentioned plate or flange preferably lies flush with the inner surface of the door while the plate portion 20 lies exposed along the edge of the door and may be of a width substantially equal to the thickness of the door. The wood of the door is partially cut away along the inner surface of the plates 20 and 21 to form a chamber or recess to receive the operating parts. The outer surface of the door, if the latter be built up of wood, may have a sheet metal covering but such has not been illustrated, as it forms no portion of my invention. The plate 20 has a pair of lugs 22 which may be formed integral therewith if the plate 20 be of cast metal or struck up therefrom if the plate be of wrought metal. If desired, the said lugs might be separate and rigidly secured in any suitable manner. These lugs serve as journals or supports for a vertically extending pivot pin 24 upon which the latch 25 is mounted. The latch member extends substantially horizontally in the general direction of the thickness of the door and has its free end mounted to swing through an aperture in the plate 20 adjacent to the flange or side wall 21. The latch itself has an outer or cam surface 26 and an inner or undercut surface 27 intersecting in a rounded edge. The curvature of the undercut side of the latch may exactly correspond to the curvature of the roller 16, although preferably it is formed as a V or curved on a smaller arc than that of the roller so that when the latch is in position on the roller, the

latter will engage with the undercut surface 27 adjacent to the edge of the latter and at a point 28 spaced a considerable distance therefrom, so that an endwise pulling on the latch tends to draw the roller into the space between the two points of contact. 70

In closing the door, the cam surface or portion of the edge adjacent thereto rides over the striker plate 18 and the catch is meanwhile swung back into the door about its pivot 24. As the edge of the latch passes the center of the roller, it immediately begins to swing out again and in so doing automatically pulls the door in toward final closed position and firmly and effectively 80 retains the same. Any tendency of the door to open or any direct pull or pressure on the latter comes substantially in the general direction of the length of the latch and as the edge of the latter has gone behind and beneath the center of the roller, the door will hold the more firmly as pressure is applied to force it open. 85

To lighten the weight of the latch and facilitate the boring of an aperture for the pivot pin 24, the pivoted end of the latch may be formed of two spaced lugs 29. 90

For mechanically and positively withdrawing the latch when it is desired to open the door, I provide a link or bar 32 lying substantially horizontally adjacent to the flange or side wall 21 and having one end pivoted in a recess in the head of the latch as shown particularly in Figure 3. I have shown a rotatable handle and also a swinging lever for pulling back on this link or bar to release the latch. Both of these may be employed or either one may be omitted without effecting the operation of the other. I have shown the side wall 21 as provided with a bracket plate 33 but having its body portion spaced from but rigidly secured to the plate 21 and one end portion secured to the plate 20. Between the bracket plate 33 and the side wall 21 and journaled for rotation in the two but held against longitudinal movement by both is a collar 34 preferably having a square aperture to receive the shaft or rod 35 projecting horizontally through the door and having any suitable form of knob or handle 36 on its outer end. The collar carries an upwardly extending pawl or arm 37 adjacent to and parallel with the plate 20 and adapted to engage with the lug or extension 39 formed integral with the link or rod 32, and guided between the bracket plate 33 and the plate 21. 100 110 115

Pivoted to the plate 21 adjacent to its lower edge is a lever arm 38 extending upwardly and guided between the bracket plate 33 and the plate 21. This normally engages with a stop 33* which may be formed as a lug on the bracket plate 33. On the opposite side of the lever arm 38 from the stop 33* is a second lug or extension 39* also 120 125 130

formed integral with or rigid with the link or rod 32. These two lugs or extensions 39 and 39^x on the link or rod 32 may be engaged by the operating members 37 and 38. Rotation of the handle 36 clockwise in respect to Figure 1 or the swinging of the lever 38 toward the right will act on the link or rod 32 through the lugs 39 and 39^x to withdraw the latch 25 when it is desired to open the door. It will be understood that the lever arm 38 may extend upwardly to a point above the upper edge of the door so that the door may be conveniently opened from the inside while the handle 36 will ordinarily be used in opening the door from the outside, particularly if the car be a closed one. The latch may be withdrawn by either the knob or the lever independently of the other, and if desired, either may be omitted without affecting the operation of the other and depending upon the construction of the door to which the device is to be applied. For an open touring car, the outside handle 36 would ordinarily be omitted although it might be placed on the inside instead of the outside of the door and the lever 38 omitted.

For holding the latch in operative position, and for preventing rattling of the parts, suitable springs are preferably employed. I have shown a spiral spring 30 mounted on a stud 31 on the plate 21 and with its free end engaging a bar 32 or a base portion of the lug 29 on the latter so as to normally shift the bar 32 to the left from the position shown in solid lines in Figure 1 and hold the latch in operative position. In addition to this spring, I may if desired, provide a second spring 41 having one end also secured to the plate 21 and the other end engaging with the lever 38 so as to normally hold it against the stop 33^x and prevent rattling.

Various changes in the details of construction and the arrangement of parts may be made without departing from the spirit of my invention. On sheet 2 I have shown a somewhat modified form, although operating on the same general principle. I have, so far as possible, employed the same reference numerals with the prime, although it does not appear to be necessary to fully describe the details of construction of this form. It will be noted that the base plate 12' is secured in position by four screws 13' instead of only two, and that the striker plate 18' rests upon one of the two adjusting screws 17'. The plate 20' is made of materially less width than the thickness of the door and carries a flange 22', the edges of which are turned in to form the lugs 23' which carry the pivot of the latch. To hold the latch in operative position, I mount the spring 30' directly on the pivot pin 24' between the two lugs 29' and form said lugs 23' with inturned ends 31', to retain the ends of the spring. I have shown the operating lever 38' and the lug or lever 37' which is operated by the rotatable handle as spaced apart at one point along their lengths and receiving the link or bar 32 therebetween. The end of the said link or bar has a head 39' with which either of the levers 37' or 38' may engage. I have also shown the lever 38' mounted directly on the collar 34' so that the two members 37' and 38' swing about the same center or axis. If it is desired to employ the rotatable handle, these two members 37' and 38' may be formed integral or may be rigidly secured together. I have shown the plate 21' as provided with a guide 40' for limiting the movement of the levers 37' and 38' and having one end constituting a stop against which the spring 41' may hold the parts against rattling. I have shown two of these springs 41' encircling a pin 42' and each having one end engaging a stop 43' and the other the corresponding operating lever. There are other minor differences, the character of which will undoubtedly be apparent from an inspection of the drawings.

In Figures 11 to 14 inclusive I have shown a modified form operating on the same general principle but differing in many features of construction. The latch member is mounted to swing in a plane substantially parallel to the edge of the door rather than about a pivot parallel to said edge and the roller retainer is mounted to project at an angle to the edge of the door casing rather than lying parallel to the latter.

In the specific construction illustrated on Sheet 3, I employ a roller retainer 27^a mounted on a pivoted pin projecting out substantially at right angles from a supporting plate 14^a. This plate may have a flange 15^a at one edge thereof which may serve as a stop to limit the closing movement of the door and said flange may have an extension or tongue 15^b for holding the outer end of the roller pivot. The plate 14^a may be secured directly to the door casing 11^a by wood screws or in any other suitable manner, or if it is desired to adjust the same, the plate 14^a may have adjustable connections to a base plate as shown in Figure 1. Ordinarily such adjustment is not necessary as the flange 15^a is at a definite predetermined distance from the roller and forms a fixed stop for the door. Secured to the door 10^a is a face plate 20^a having a flange or side wall 21^a on one side and a separate parallel side flange 22^a on the opposite edge. This flange 22^a has an extension 23^a substantially parallel to the plate 20^a and between the two is mounted a pivot pin 24^a for the latch 25^a. The latter is mounted to swing in a substantially vertical plane and normally extends in a direction transverse to the thickness of the door. Above the pivot pin 24^a may be a spring 30^a

4
mounted on a pin or other support 31^a so as to normally press downwardly the free end of the latch which extends toward the side wall or flange 21^a.

- 5 The plate 20^a has a slot 50 extending inwardly from the edge thereof bearing flange 21^a and said flange has a corresponding slot, these slots being of such length and width as to permit the entry of the roller 27^a 10 through the slot in the general direction of the length of the latch so that as it engages the outer curved cam surface of the latch, it will lift the latch against the action of the spring 30^a until the edge of the latch passes 15 over the roller and the latter is gripped and retained against the undercut surface of the roller, as will be readily understood from the previous description of the form shown in Figure 1.
- 20 For raising the latch, any suitable operating mechanism may be employed. A simple form is a bell-crank lever 38^a mounted on a pivot pin 34^a on the side wall 21^a. The lower substantially horizontal leg of 25 the lever may have a laterally extending apertured flange 52 receiving the upper end of a link 32^a, the lower end of which is pivoted to the free end of the latch and the upper end of which is provided with a head 39^a. For normally holding the lever in pre- 30 determined position, a spring 41^a may be mounted on a pin 42^a and have one end engaging with the stop on the lever and the other end with the stop on the side wall 21^a.
- 35 This last mentioned stop may be so positioned as to co-operate with a second stop 40^a and limit the swinging movement of the lever. In case it is desired to operate the latch shown in Sheet 3 by a knob, it will be 40 evident that I may combine with the lever shown a knob operated mechanism somewhat similar to the parts 34 and 37 inclusive of Sheet 1.

45 It will be noted that in this form, the latch does not at any time project beyond the door but merely swings into or out of operative position in respect to the slot 50 which receives the retainer roller.

50 In all of the forms illustrated in the accompanying drawings, the latch retainer is in the form of a roller free to rotate as the latch engages therewith. This is important in that it acts to very materially reduce the friction and facilitate the operation of the parts, but so far as the mechanical construction or operation of the latch is concerned, it might co-operate with a retainer in the 55 form of a non-rotatable rod or other member presenting a suitable retaining surface. With the shape of latch illustrated, such re-

taining surface would preferably be a curved one.

Having thus described my invention, what I claim as new, and desire to secure by Letters Patent is:

- 65 1. In combination, a plate adapted to be secured to one surface of a door and having a plate portion integral therewith adapted to extend along the edge of the door, a latch pivotally secured to said second mentioned plate, a link slidably mounted upon said first mentioned plate and secured to said latch, and a rotatable handle and a swinging handle having independent operative engagement with said link for 70 withdrawing said latch.
2. In combination, a plate adapted to be secured to one side of a door and having a second plate portion at an angle thereto and adapted to extend along the edge of a 75 door, said plate portion having an aperture therethrough, a latch member pivoted to said plate portion at one side of said aperture and having a portion movable through the latter, a link slidable along the 80 inner surface of said first mentioned plate and having one end pivotally connected to said latch, and having a pair of lugs or projections thereon, a rotatable member carried by said first mentioned plate for en- 85 gaging with one of said lugs to withdraw the latch, and a swinging member pivotally mounted on said first mentioned plate for engaging with the other lug for independently withdrawing the latch. 90
3. In combination, a plate adapted to be secured to a door, a latch pivoted thereto, a link connected to said latch, a pair of lever arms for independent engagement with said link to withdraw the latter and 95 said latch, a rotatable member for swinging one of said lever arms and a handle connected to said rotatable member, the other of said lever arms projecting vertically through the upper edge of the door and 100 serving as a handle.
4. A latch casing, having a face plate, spaced lugs at one edge thereof, a pivot pin supported by said lugs, a latch having spaced lugs mounted on said pivot pin adjacent to 105 said first mentioned lugs, and a coil spring on said pivot pin intermediate of the lugs of the latch and having a portion engaging with the body of the latch and a portion moved laterally and caught beneath a 110 portion of one of said first mentioned lugs. 115

Signed at New York city in the county of New York and State of New York this 2d day of July A. D. 1919.

PETER A. SCHWAB.
